UNITED STATES PATENT OFFICE.

HENRY C. SMITH, OF SOMERVILLE, MASSACHUSETTS.

METAL WINDOW FRAME AND SASH.

SPECIFICATION forming part of Letters Patent No. 651,123, dated June 5, 1900.

Application filed August 24, 1899. Serial No. 728,325. (No model.)

To all whom it may concern:

Be it known that I, HENRY C. SMITH, a citizen of the United States, residing at Somerville, in the county of Middlesex and State of Massachusetts, have invented a new and useful Improvement in Metal Window Frames and Sashes, of which the following is a full, clear, and exact description, reference being had to the accompanying drawings, forming a part of this specification, in explaining its nature.

The invention relates to the metal window-frame and window-sash and means for hanging the sashes hereinafter described. It is especially adapted for use in manufacturing and commercial buildings.

Referring to the drawings, Figure 1 is a vertical section of my improved window frame and sash. Fig. 2 is a vertical section on the line 2 2 of Fig. 1. Fig. 3 is a horizontal section on the line 3 3 of Fig. 1. Fig. 4 is a perspective view of a portion of the frame. Fig. 5 is a perspective view of a portion of the sash-rail. Fig. 6 is a detail.

In the drawings, A represents one of the sides of the window-frame, B the sill, and C the top or head of the frame. The side sections are alike in construction. Each is made, preferably, of a single piece of sheet metal, which is shaped or formed to provide first the flanges a^1 near each edge of the section and which extend from the inner side of the section preferably, at a right angle thereto, and which are embedded in the masonry of the wall or attached to wooden furlings if the wall be of wood, and they serve to anchor and stay the frame in position. The piece is also shaped to provide the inner molding a^2 and the outer molding a^3 , the surfaces a^4 a^5 of which bear against the faces of the masonry or of a casing of wood, and the outer or exposed surfaces of these moldings may be of any desired configuration. The molding a^3 also has a face a^6 , which acts as an outer stop or flange, against which the outer window-sash bears. The side section also has formed from the piece the deep shallow recesses a^7 a^8 , which extend the full length of the section and receive guiding rails or pieces C' C², respectively, the first attached to the upper window-sash and the second to the lower window-sash. These guiding-pieces are preferably of thin

bar-iron, and they extend into the recesses a^7 a^8 very nearly to the bottom thereof, and they furnish means by which the sashes are attached to the frame and arranged to slide thereon.

It will be understood that each sash may have the flanges upon one side only or upon both sides, as may be preferred, and they are arranged to extend above the upper rail of each sash and to also have a lateral movement from the side rail of each sash for the purpose of permitting the sashes to be placed in the frame and the engagement between the sashes and the frame by the flanges to then be made. Each side rail D of the sash having one of these flange-pieces is provided with a deep recess d, opening on the edge and of sufficient depth to permit the flange-piece to be entirely contained therein, so that its outward edge shall not project from the outer edge of the rail. This permits the flange-piece to be "housed," so to speak, in the outer rail preparatory to mounting the window-sash in the frame. After the sash has been placed in the frame the flange-piece is moved outward from the side rail to enter one of the recesses of the frame.

In Fig. 3 I have shown the flange-piece in dotted lines as housed and in full lines as moved outward to engage the window-sash with the frame. To move the flange-piece outward after the sash has been placed in the frame, I have provided each flange-piece with one or more inclined slots c, (preferably two are used,) and have extended through each slot a pin c', fast to the window-sash, and by moving the flange-piece vertically upward it is caused to be moved at the same time outwardly and to enter the frame-recess. On the other hand, by moving the flange-piece downward it is moved inward in its pocket d. When the flange-piece has been moved upward and outward, it exposes at its upper end a hole e, which is adapted to receive one end of a balancing tape or cord E, which extends therefrom upward about a fixed pulley e' and then downward and has its other end fastened to the upper end of the flange-piece of the other sash. When the flanges are used upon one side only of the sashes, the other chain or cord of the two necessary for hanging the sashes has its ends connected directly

with the sashes. By this construction it will be seen that one sash serves to balance the other sash, as the tape or cords connect the upper bars or sections of the two sashes, and if one sash is lighter than the other it may be weighted to balance the other. This may be done by the addition of a weight or the addition of spring-pressure to bear against one or the other of the two sashes, and when it is desired that the windows automatically close in case of fire it will be necessary to make the lower sash heavier than the upper sash and to then hold the upper sash open by any device which shall be caused to become inoperative for that purpose upon the presence of the heat of the fire. One way of accomplishing this I have represented in Fig. 2, where I have shown a spring attached to the sash and arranged to bear against the side of the frame with sufficient stress to hold both sashes open in any position to which they may be moved. This spring I have lettered E', and it is shown (partly in dotted lines) as a bow leaf-spring, which is attached to the upper part of the upper sash at e' by a solder fusible at a relatively-low temperature. Normally it presses against the side of the frame and holds the sash in place; but when the fusing temperature of the solder is reached the spring becomes detached from the sash and the material weight of the lower sash will then cause it not only to drop and close, but will also enable it to lift and close the upper sash.

It will be seen that each side section of the frame is of one thickness of metal and forms a cavity open at the back, and I prefer that this entire cavity shall be filled with mortar or cement, preferably after the frame has been set in place, and in the drawings A' represents the mortar or cement in said cavity. The side sections of the frame are connected together by the sill B. This is also made of one piece of metal shaped to the configuration of a usual wooden sill—that is, it has the inner side b, the outer side b', the front stop b², and the inclined portion b³. It is joined at its ends to the lower ends of the side pieces by riveting or in any other desired way, and its cavity b⁴ is also preferably filled with brick, mortar, cement, or other non-combustible material. The upper ends of the side sections of the frame are connected by the head C. This is also made of one piece of metal and has any desired configuration. The side sections of the frame are riveted or otherwise united to it, and it is stiffened by cross-stays c, which are riveted to the inner side c⁴, the outer side c⁵, and bottom c⁶. It is open at its top, and its cavity c⁸ is filled with brick, mortar, cement, or other non-combustible, if desired. It is preferably provided with inward-extending sections c⁷ c⁸ from its upper corners to provide a surface upon which the mortar may be laid to form a joint between it and the wood or brick work above it.

The side rail of each window-sash bearing the flange-piece C is preferably formed, as represented in Fig. 3, of three pieces of flat metal plate d' d² d³. The piece d' forms the outer vertical side of the rail and is also shaped with the deep recess d. The piece d² forms both the outer and inner faces of the rail and the inner side of the rail. It is also shaped to provide the glass shoulder d⁴ and to form a section of a joint d⁵, to which the glass-retainer d⁶ is secured. It is united at d⁷ by any suitable joint with the outer edge plate d'. The piece d⁸ forms a glass-retainer and is united to the piece d², as above specified and as shown in Figs. 3 and 5. It is detachably secured to said plate, its flange d⁷ being adapted to enter a receiving-recess d⁹, formed in said plate d' and upon the inner face thereof or the face opposite the shoulder d⁴. The side rails of the sash are connected at their upper and lower ends with the cross-rails, preferably by riveting, and these rails are preferably made of metal plates of substantially the shape of the side rails without the pocket. If only one flange-piece is used for each sash, the other side rail will be made without the pocket d, and the piece d' would then have formed on it an outward-extending integral tongue d⁹, (see Fig. 6,) which enters the recess a⁷ of the section of the window-frame on that side.

The advantages of the invention arise from the simplicity and the cheapness of the construction and also from its fireproof character and from the manner of hanging the window-sashes, whereby weights are dispensed with as well as holes through the side sections of the sash-frames and solid fireproof frames provided and cavities within the same and also the automatic closing of the sashes in case of fire. I would further say that the construction permits of the use of window-frames having very narrow side sections, and thus enables wider sashes to be used, thus increasing the lighting efficiency of the windows as compared with frames and sashes of the same width where the sashes are hung by weights in the ordinary way.

Having thus fully described my invention, I claim and desire to secure by Letters Patent of the United States—

1. In a metallic window-casing the side sections of the frame having the stop-bead a⁶ and the guiding-recesses a⁷, a⁸, as and for the purposes described.

2. In a metallic window-casing the side sections made from a single thickness of sheet metal, shaped to provide the anchoring ends a, a', an outer molding, the stop-bead a⁶, the guiding-recesses a⁷, a⁸ and the moldings a³, a², as and for the purposes described.

3. A metallic window-sash provided with side rails having a deep recess in one or both of said rails extending to the edge of the rail and a flat metal plate or tongue adapted to be contained in whole or in part in said recess

and to be moved outward therefrom and to be locked to the sash in its said last-named position, as and for the purposes described.

4. A metallic window-sash provided with 5 side rails having a deep recess in one or both of said rails extending to the edge of the rail and a flat metal plate or tongue adapted to be contained in whole or in part in said recess and to be moved outward therefrom and 10 to be locked to the sash in its said last-named position, in combination with a window-frame having in its side section a vertical recess or recesses into which a part of said metal plate or tongue is adapted to enter 15 when moved outward from the sash-rail, and which plate or tongue is movable with the sash and serves to attach the sash to the casing.

5. The combination of the window - sash having a vertical recess in its end rail, a metal 20 plate or tongue contained in said recess, means for moving said plate or tongue outwardly from said sash comprising the pins *c'* extending across the recess and inclined slots *c* in the plate or tongue through which the pins 25 extend, and whereby a slight upward movement of said plate or tongue in its recess also causes its outward movement.

6. The combination of the metallic window-sashes, extension tongues or plates movable 30 laterally from the side rails thereof to make engagement with the window-frame and sash cords or chains attached by their ends to the said sashes and passing over pulleys at or near the top of the frame, whereby one sash 35 is caused in whole or in part to balance the other.

7. The combination of the metallic window-sashes, metallic extension-plates upon one or

both sides thereof which are moved outward therefrom to make engagement with the window-frame upon a slight vertical movement thereof, window cords or chains connecting the extension-pieces of one sash with those of the other, pulleys over which said cord or chain extends, the weight of the sashes on 45 said cords or chains serving to maintain the extension-pieces in their outermost or frame-engaging position, as and for the purposes described.

8. The combination of two metal sashes, 50 one of which is heavier than the other, and which are connected together by sash cords or chains so that one partially balances the other, and a friction-spring attached to one of the window-sashes to bear against the window-frame to act as a means for maintaining an equilibrium between the two sashes, the 55 said spring being operative by solder which is fusible at a relatively-low temperature, and whereby upon the release of the spring the 60 heavier sash will then overbalance the other sash and cause both to automatically close.

9. The combination in a window-sash of a side rail made of three pieces of metal, one of which forms the outer edge and a deep recess, the other of which forms the two sides, inner edge and shoulder and a section of a joint for holding a glass-retainer, and which is interlocked with the first-named piece, and the third of which is a glass-retainer and a 70 section of a joint combining with the joint-section of the second piece.

HENRY C. SMITH.
